START-STOP REGENERATIVE REPEATER

Walter J. Zenner, Des Plaines, and Stephen Janiszewski, Chicago, Ill., assignors to Teletype Corporation, Chicago, Ill., a corporation of Delaware

Application May 23, 1936, Serial No. 81,410
Renewed August 25, 1937

9 Claims. (Cl. 178—70)

This invention pertains to telegraph systems of the start-stop type in which code signals are repeated from line section to line section, and more particularly, to regenerative repeater mechanisms for start-stop telegraph systems.

The object of the present invention is to provide a start-stop regenerative repeater of simple design and capable of easy and accurate adjustment into an operating condition both during and after assembly.

The above and other objects are attained by providing separate and independent adjusting means for the several cam followers for positioning them adjustably in the planes of their respective controlling cams, relatively adjustable arms upon a controlling lever or jockey which operates to receive cam control from a cam surface at the extremity of one arm and to deliver cam control from a cam surface at the extremity of another arm, an adjustable stop member for the angular movement of the said jockey, an adjustably mounted pivot post for the said jockey, propelling means and stopping means for a contact arm and effective to control the arm by mechanical contacts at closely associated points of engagement, means for adjusting the mechanical position of the repeater to effect desired and proper engagement of its driven gear with a driving gear, means to adjust the electromagnetic system of the repeater mechanism and to readjust it while in operation, and other details of convenience in the construction and operation of the device.

The present invention provides a modified form of a structure disclosed in copending application Serial No. 712,461, filed February 23, 1934 by Walter J. Zenner for "Start-stop regenerative repeater."

A better understanding of the invention may be had from the following description, taken in conjunction with the accompanying drawing, wherein,

Fig. 1 is a plan view of a mechanism embodying the invention, with upper portions omitted as indicated by line 1—1 in Fig. 2;

Fig. 2 is a sectional view taken on line 2—2 in Fig. 1;

Fig. 3 is a sectional view taken on line 3—3 in Fig. 1; and

Fig. 4 is a sectional view taken on line 4—4 in Fig. 1.

Referring to Figs. 1 and 2, a frame structure comprises a base plate 10 and a base casting 11 united by screws 12. Upon the basic structure all operating parts of the repeater are mounted.

An operating cam shaft 13 has integral sections 14 and 15 of larger diameter journaled in the base casting 11 and has other sections 16 and 17 upon which parts are assembled to turn with the shaft, some in fixed relation and others in adjustable relation. Hub 18 is fixed upon shaft section 16 by a set screw and bears a driven repeater gear 19 fixed upon hub 18 by a lock nut. 5

A cam sleeve 20 has assembled upon it a stop arm 21, a flutter cam 22, an off-normal cam 23, a timing cam 24, a lock nut and a threaded flange disc 25, all with spacing rings interposed. The outer end of the cam sleeve 20 has an integral flange 26 as shown, and the tubular end of cam sleeve 20 is threaded with right-hand 15 thread which is engaged by the lock nut to fix the stop arm and all cams upon the cam sleeve, after which threaded flange 25 is assembled upon the end of the cam sleeve. A slightly larger section of shaft section 17 is threaded to carry an 20 adjustable nut 27 which engages one end of a shaft-encircling spiral spring 28 whose other end engages a loose flange 29 splined to revolve with the cam shaft 13. At the end of shaft section 17 an internal left-hand thread is tapped into 25 which a threaded stud of flange 30 is screwed tightly, an annulus 31 of friction material having been positioned between the flanges 26, 30, and a similar annulus between the flanges 25, 29. Adjustable nut 27 now is turned to produce a 30 desired tension in spring 28, the assembled cam shaft 13 is placed in the journal bore of the base casting 11, lock nut 32 and cut nut 33 are installed upon the threaded end of base casting 11, and hub 18 with gear 19 is fixed upon the 35 shaft section 16.

Cam shaft 13 is designed to rotate continuously by energy received from a motor (not shown), and cam sleeve 20 is designed to be latched against rotation in start-stop manner. Latching mechanism comprises a gate latch 34 on pivot stud 35, a retractile spring for latch 34 (not shown), a rocking lever 36 with compression spring, a bell crank lever 37, a push pin 38, and an adjustable striker 39 on armature 40. The 40 angular position of cam sleeve 20 and its cams when latched by engagement of stop arm 21 and gate latch 34 is variable for purposes of orientation by means of pivoted plate 41, pivoted upon shoulder screw 50 in fixed frame plate 51 and 45 having indicator arm 52 with lock nut 53 cooperating with a calibrated scale on plate 51.

In operation, with magnets 54 energized and with armature 40 in its operated or attracted position, lever 36 is rocked by its spring to ob- 55

struct the gate latch 34 and to cause pin 38 to protrude, shaft 13 rotates continuously and through friction members 31 urges cam sleeve 20 to press stop arm 21 against the obstructing gate latch 34 which in turn is obstructed by lever 36. Deenergization of magnets 54 in response to an electrical signal releases armature 40 which, propelled by its retractile spring 55, Fig. 1, moves striker 39 to push the pin 38 which 5 operates bell crank lever 37 and rocking lever 36 to release gate latch 34, thus releasing stop arm 21 and permitting the cam sleeve 20 to turn by power transmitted through the friction members 31. Timing cam 24 strikes its follower 51 10 at the instant of beginning of each repeated signal impulse, flutter cam 22 strikes its follower 53 and thereby propels armature 40 toward magnets 54 just prior to each operation of follower 51 after its first operation in each code cycle, and 15 off-normal cam 23, through lever 60, permits its contact springs 59 to close during a period of substantially the full revolution of the cam sleeve 20, reopening its springs 59 just before the cam sleeve is stopped by reengagement with the gate latch.

An armature carrier 61, of which cam follower arm 58 is an integral part, is pivotally supported upon the extension sections of two shouldered screws 62, Fig. 3, and is restrained against axial 20 translation by the shoulders thereof. Screws 62 are threaded into tapped holes in casting 63 in the axis of the boss 64 and pivotally support also upon their extended sections the contact lever 65 which is restrained against axial translation by 25 abutment with the ends of the screws 62. Armature carrier 61 and contact arm 65 thus are pivoted coaxially for independent movement and are articulated through two substantially straight springs 66 whose proximal ends are attached to 30 armature carrier 61 by means of clamp 67 and whose distal ends engage the two sides respectively of contact arm 65. By provision of long and substantially straight springs instead of short coiled springs, it is possible to apply spring 35 propelling force at a contact point near the points of application of mechanical restraint, at the same time preserving the feature of minimum weight for all oscillatory parts. Contact arm 65 bears a contact support member 70 40 clamped between plates of insulating material by screws 71 to which are attached two pairs of flexible contacts 72 and a flexible conductor 73, all electrically united but insulated from the arm 65. In one position of contact arm 65, the 45 flexible contact springs 72 engage both contact screws 74 and in the alternative position of arm 65, the springs 72 engage both contact screws 75.

In operation, when contact arm 65 is in spacing position as shown and when armature carrier 61 moves to marking position by power from flutter cam 22 and when armature 40 then is held in marking position by energized condition of magnets 54, the lower one of springs 66 will urge contact lever 65 upward and cam 24 will strike 50 its follower 51 to cause a cam surface 76 on arm 77 to release arm 65, thus permitting arm 65 to follow the armature carrier 61 into marking position and to shift the flexible contacts 72 out of engagement from contact screws 74 and into engagement with contact screws 75. Alternative 55 or reverse operation of the same parts is obvious.

A novel design of contact post for carrying two contact screws is provided, comprising an integral metal base part 79, Fig. 3, having two clamp jaws 80 and a single clamp screw 81 for the

two contact screws, and having an elastic neck 82 for at least one of the clamp jaws with a hinge axis or axis of elastic yield 83 so related to the positions of the two contact screws that approximately equal clamp pressure is applied ultimately by the one clamp screw to the two contact screws. 5

Tight and loose jockeys are provided for pivoted arm 65 which carries repeating contacts 72 and is propelled in oscillating manner at pre-determined moments by power received from armature 40 through one or the other of the two straight springs 66. A loose jockey 84 pivotally supported upon the base plate 10 and lightly tensioned by spring 85 engages the pivoted arm 15 65 with cam faces near the points of engagement of the springs 66; either spring, when tensioned to move the pivoted arm 65, being sufficiently strong to overcome the loose jockey, and the loose jockey being at all times tensioned 20 sufficiently to prevent vibration of the pivoted arm from bounce or inherent periodicity or other minor cause. A tight jockey 86 strongly spring tensioned by its spring 87 has a cam arm 77 which engages the pivoted arm 65 upon radial or 25 slightly cammed faces near the points of engagement of the springs 66 and is tensioned sufficiently to hold the pivoted arm 65 against all spring urges, the tight jockey being mechanically operated by timing cam 24 to abandon the pivoted arm 65 to control by its propelling springs at 30 predetermined moments. It is advantageous to have all springs and jockeys engage the pivoted arm at points closely grouped. When the two straight springs 66 are fabricated from round 35 wire, as shown, union of the two springs at their proximal ends prevents axial rotation of either one of the springs.

Tight jockey timing adjustment is effected by provision of a mounting arm 89 adjustable in 40 angular position around a fixed pivot post 90 to support a movable pivot post 91 upon which the tight jockey rocks, the arrangement of parts being such that, by angular movement of the mounting arm, a resultant movement is effected 45 of cam follower 57 integral with the tight jockey along the periphery of its rotatable controlling cam 24. A principal orientation mechanism in the repeater effects orientation of all cam followers with reference to the starting position of 50 the several cams as determined by the stop arm 21 and gate latch 34, and in addition, as a further device for orientation adjustment, the movable pivot post 91 for the tight jockey effects an adjustment of the jockey cam follower with 55 reference to the starting position of its cam and without modifying coexistent adjustments between other cam followers and the starting positions of their cams, respectively.

The tight jockey 86 comprises two arms, one of 60 which 57 is a cam follower for receiving controlling motion from a motor driven cam 24, and the other of which 77 has the nature of a cam with cam faces 76 on an extension whose follower is the pivoted contact arm 65. When a desirable 65 adjustment of the cam follower arm 57 of the jockey has been attained by means of eccentric shoulder screw 92, angularly adjustable mounting arm 89, and the movable pivot post 91 supported thereby, it may be desirable to change the position 70 of the cam arm 77 of the jockey relative to its follower, the pivoted contact arm. There are provided for this purpose two separate arms 57 and 77 for the tight jockey, pivoted upon the pivot post 91 coaxially and independently, and 75

articulated by a screw threaded into one of the arms and passing through a slot in the other of the arms. The cam arm 71 of the jockey may be adjusted to its desired position without changing the position of the cam follower arm 57, the arms then being clamped together by the screw 93.

An off-normal switch for prevention of reflection signals is provided, comprising a pair of cam controlled contact springs and contacts 59 which are disengaged from each other by cam 23 and cam follower 60, while the repeater mechanism is in normal or stopped condition, but which engage together when the cam sleeve 20 and cam 23 are in any other angular position. When two of the repeating mechanisms herein illustrated are used in a single repeating system which transmits in two ways alternatively upon a single channel of communication, operating the repeating mechanisms alternatively in so doing, the cam controlled contacts 59 in an operating repeating device disable a companion repeating device to prevent reflection signals. It is required that the cam controlled contact springs be in open condition when the cam 23 is at rest, regardless of the orientation position of adjustment of the cam 23. Accordingly, there has been provided for the springs a support or carrier 95 rotatable coaxially with the cam sleeve 20 and rotatable under control of the principal orientation mechanism to maintain unchanged the relation between and among the contact springs 59, their cam 23 and the cam follower 60 associating the springs and the cam. An annular rib is provided by base casting 11 which projects above the base plate 10 of the repeater mechanism, surrounding the cam shaft and surrounded by an inner annular edge of a ring of the carrier 95, a portion of the ring of carrier 95 being omitted to permit the yoke-shaped remainder to pass the cam sleeve 20 and to take its position upon the annular rib after assembly of the cam shaft 13 and the base structure 10, 11. A clamp member 96 of spring nature, shaped to resemble a part of a ring, holds the carrier 95 rotatable around the cam shaft 13 under friction between the base plate and the clamping member, a similar member 97 of spring nature being positioned between carrier 95 and base 10 in the manner of a shim. Control of the spring carrying member 95 by the principal orientation mechanism is attained by providing in the rotatable spring carrier 95 a notch 98 which spans the stud or screw 35 in the principal orientation mechanism, thereby rotating the spring carriage 95 by the principal orientation device whenever the cam sleeve 20 is rotated thereby.

As a process of assembly in course of construction of the repeater, it will be desired to align the several cam followers into the planes of their respective controlling cams.

Mechanical construction of the several members and particularly the length of the movable pivot post 91 will determine the dimension from the face of the base plate 10 to the plane of the cam arm 57 of the tight jockey 86, and provision is made by cup nut 33 and its lock nut 32 to adjust the controlling cam 24 into the plane of its follower 57. The cam shaft 13 has fixed upon it a gear hub 18 having a crown face near and opposing a crown face of a shoulder 15 upon the shaft, and between these two crown faces is confined a web of cup nut 33 which is threaded to the frame casting 11 of the repeater base structure. An adjusted position of the cup nut 33

therefore, determines an adjusted axial position of the cam shaft 13, and such adjustment varies the position of the plane of the cam 24 with relation to its follower, the tight jockey arm 57. The cup nut 33 may be turned until a desired relation of cam and follower is attained and the lock nut then may be tightened to retain the adjustment. 53

Subsequently to adjustment of the cup nut 33 and cam 24, the follower 60 of off-normal switch 59 may be adjusted into the plane of its cam 23 by changing the thickness or by changing the number of friction rings 97 between the off-normal switch carrier 95 and the face of the base plate 16 according to well-known practice with shims. 107

Also subsequently to adjustment of the cup nut 33, the cam follower 58 integral with armature carrier 61 may be brought into the plane of its controlling cam 22 by adjustment of its two shouldered pivotal screws 62, Fig. 3, retiring one screw and advancing the other to position the armature carrier 61 at the distance desired from the face of the base plate 10 to bring its cam follower 58 into the plane of its cam 22.

An abutment for the arm 77 of the jockey 86 to determine dimension of engaging cam surfaces 76 between the arm 77 and the pivoted contact arm 65 is provided in a radial yoke member 99 attached adjustably to the fixed stud 90 and having its distal end formed into a yoke which spans the arm 77 of the jockey at a location near the cam faces 76 of the jockey arm. The radial yoke member surrounds the fixed post 90 by a closely fitted hole having a radial slot, and a bolt and nut 100 with lock washer is provided to draw together the sides of the radial slot, thereby clamping the member 99 firmly upon the fixed post 90.

A plurality of repeater mechanisms as illustrated herein are assembled upon a frame or rack 101 which is equipped with a motor (not shown), motor driven shafting 102, and motor driven gear 103, a motor driven gear being provided at the location of each and every proposed repeater. Screw tapped mounting holes are provided in the assembly rack located at predetermined distances from each gear 103 and these distances are comparable to related distances in each repeater. Each repeater also contains a gear 19 designed to mesh with one of the gears 103 on the assembly rack 101. When a repeater is mounted by screws engaging the base plate of the repeater and threaded into the noted tapped holes in the assembly rack, the gear 19 of the repeater will mesh the gear 103 of the rack and provision is made for minor adjustment to produce a satisfactory depth of meshing between the teeth of the two 40 45 50 55

depth of meshing between the teeth of the two gears. Near the lower edge of the repeater base plate, two bosses 104 are provided, shaped to present substantially spherical faces 105 against the rack 101 which is suitably countersunk. Each boss 104 is drilled to provide ample clearance for a mounting screw 106, the function of positioning the repeater upon the rack being effected by engagement of two spherical surfaces, not by engagement of any boss 104 with the body of a mounting screw. Near the upper edge of the repeater base plate 10, a tapped hole 107 is provided in a location approximately coaxial with a tapped hole 108 of larger diameter in the rack 101. A tubular adjusting member 109 is externally threaded to cooperate with the tapped hole 108 of the rack and has an internal diameter offering ample clearance for a screw 110 engaging the tapped hole 107 of the base plate 10 of the repeater. A polygonal flange 111 projecting beyond the head of screw 110 permits a spanner 75

wrench to turn the tubular screw member 109. Adjustment by moving the repeater gear wheel in relation to the rack gear wheel is effected by adjusting the three mounting screws closely, but not tightly, then turning the tubular screw member 109 to push the upper edge of the repeater base plate 10 from the rack 101, thus swinging the repeater base plate upon its bosses 104 as upon a pair of hinges, and thus rotating the entire repeater mechanism to cause the repeater gear 19 to approach more closely the rack gear 103, or conversely. When desired adjustment has been attained, the three mounting screws are tightened, and their split ring lock washers assist them in retaining the gears in adjusted position.

Subsequently to connection of the winding of the electromagnet into the circuit of a telegraph line, adjustment of the interstice of the core and armature may be required to adapt the magnetic system to the electrical constants of the specific line into which it has been connected. Accordingly, there is provided means for moving the magnets 54, comprising pivotal means for governing the path of movement of the magnets, and micrometric means for producing movement of the magnets and for controlling the extent of movement and for preserving a condition of adjustment. The magnet cores are mounted upon a casting 63 having a flat face engaging the face of the base plate 10 of the repeater and having the cylindrical boss 64 projecting from the flat face and entering a circular hole in the base plate whose edges are engaged closely, thus forming a journaled articulation. A threaded member or adjusting screw 112 is threaded into a tapped hole in the casting 63 and has a pair of crown faces 113 which engage closely the sides of a pin 114 fixed in the base plate 10. By virtue of engagement of its crown faces with the fixed pin, the adjusting screw 112 does not move axially when turned, resulting, therefore, in a movement of the casting 63 and of the magnet cores, thus varying the interstice of cores and armature 40. Screws 115 threaded into the base plate pass through slots in the casting 65 and clamp the casting firmly to the base plate when a desired condition of adjustment has been attained.

The present invention, having been described above in connection with illustration of a specific embodiment thereof, now will be considered more generally and from a contemplation of its broader scope, and will be definitely pointed out in the claims without limitation to the specific illustration utilized herein for teaching the invention and its application to the prior art.

What is claimed is:

1. In a start-stop telegraph repeater, a structural frame, a rotary shaft journaled in said frame, a plurality of coaxial rotary cams occupying relatively fixed separate planes upon said shaft, cam followers for said cams severally and separately mounted on said frame, a pair of oppositely faced annular shoulders upon said shaft, and a screw threaded member adjustably engaged with said frame and engaging said two annular shoulders to control adjustably the axial position of said shaft to align a cam with its associated cam follower.

2. In a start-stop telegraph repeater, a structural frame, a rotary shaft journaled in said frame, a plurality of coaxial rotary cams in relatively fixed separate planes upon said shaft, cam followers for said cams separately mounted on said frame, means engaging said frame and said shaft for moving said shaft and all of said cams

relatively to all of said cam followers to vary the relation of the planes occupied by said cams with the planes occupied by said cam followers, and means comprising a pair of shouldered screws whose threads engage said frame and whose shoulders and extension sections engage one of said cam followers for moving one of said cam followers to vary the relation of the planes occupied by said one of the cam followers and its associated cam.

3. In a start-stop telegraph repeater, a structural frame, a cam shaft journaled in said frame, a cam assembly member comprising a plurality of coaxial rotary cams in fixed axial and angular relations carried by said shaft, cam followers for said cams, means carried by said frame and engaging said cam assembly and adjustable to vary the angular relations between a plurality of said cams and their associated cam followers, and further means carried by said frame and engaging one of said cam followers and adjustable to vary the angular relation between a cam and its associated cam follower.

4. In a start-stop telegraph repeater, a plurality of rotary cams, cam followers for each of said cams, means for adjusting simultaneously the orientation of a plurality of said cams, and further means for adjusting the orientation of one of said plurality of cams.

5. In a start-stop telegraph repeater, a signal receiving armature, a rotary cam, a cam follower engaging said cam and controlling said armature, a retransmitting contact member, a further rotary cam, a further cam follower engaging said further cam and controlling said retransmitting contact member, said cam and said further cam fixed together, joint orientation means for said cams, and means comprising an adjustably positioned pivot for one of said cam followers for varying the relation of operating times of said signal receiving armature and of said retransmitting contact member.

6. In a regenerative start-stop telegraph repeater, a retransmission cam, a pivoted follower arm for said retransmission cam, a retransmitting contact member, a pivoted controller arm for said retransmitting contact member, said follower arm and said controller arm pivoted coaxially upon a common pivot adjustable with respect to said cam, means for uniting said follower arm and said controller arm at a desired angular relation, and a double stop member for said controller arm having front and back stops for said controller arm in fixed relation to each other and jointly adjustable to a desired position, said stops engaging said controller arm at mechanical contact points adjacent the point of engagement of said controller arm and said retransmitting contact member.

7. In a regenerative start-stop repeater, a retransmitting contact member, a signal responsive armature, said member and said armature pivoted coaxially, a plurality of straight springs engaging said member and said armature controlled by said armature and tending to urge said member, a jockey engaging said member and spring tensioned to yield to movement of said member when urged by said straight springs, and a holding jockey having engagement with said member, the contact points of mechanical engagement of said member with said straight springs, said jockey, and said holding jockey being closely grouped upon said member.

8. In a regenerative start-stop telegraph repeater, a retransmitting contact arm, means for

operating said arm in start-stop manner, a pair of retransmitting contact members attached to said arm, said contact members electrically connected together, a pair of adjustable contact screws having contact points engageable concurrently by said contact members, and a supporting clamping bracket for said contact screws comprising a unitary electrically conductive member having a body portion and two clamp jaws tapped for two contact screws, said jaws connected to said body portion by hinge portions and relatively movable with respect to each other upon a hinge line parallel to a plane through axes of said two contact screws whereby by relative movement of said jaws said two contact screws both will be clamped, and a single clamp screw engaging both of said jaws to draw said jaws into clamping relation with said contact screws.

9. In a power driven telegraph repeater, a power shaft, a power gear carried by said shaft, a driven gear, a repeater frame upon which said

driven gear is carried, a rack frame upon which said power shaft and power gear are carried, hinge members comprising bosses with spherical surfaces and loosely engaging screws engaging said repeater frame with said rack frame for limited relative rotation to produce a desired adjustment of intermeshing of teeth between said gears, rotation control means comprising a threaded tubular member engaging a tapped hole in said rack frame and abutting said repeater frame, a screw engaging a tapped hole in said repeater frame and passing through said threaded tubular member to clamp said repeater frame to said threaded tubular member and to clamp said tubular member against rotation in said rack frame, and means for turning said threaded tubular member, said means for turning and said gears being upon one and the same side of said rack frame.
